UNITED STATES PATENT OFFICE

147,956

DESIGN FOR A ROSARY

George R. Burck, Washington, D. C.

Application August 15, 1947, Serial No. 140,881

Term of patent 14 years

(Cl. D45—16)

To all whom it may concern:

Be it known that I, George R. Burck, a citizen of the United States, residing at Washington, in the District of Columbia, have invented a new, original, and ornamental Design for a Rosary, of which the following is a specification, reference being had to the accompanying drawing, forming part thereof.

The present application is a continuation-in-part of my earlier applications Serial Numbers D. 118,078, filed February 21, 1945, and D. 122,513, filed October 4, 1945.

In the accompanying drawing:

Fig. 1 is an elevational view of a rosary showing my new design;

Fig. 2 is an enlarged front view of one of the spheroidal transparent beads of the rosary, the solid image therein being lined for color contrast;

Fig. 3 is a side view of the bead shown in Fig. 2;

Fig. 4 is a sectional view taken on line 4—4 of Fig. 2;

Fig. 5 is an enlarged front view of another of the spheroidal transparent beads of the rosary,

the solid image therein being lined for color contrast;

Fig. 6 is a side view of the bead shown in Fig. 5.

I claim:

The ornamental design for a rosary, substantially as shown and described.

GEORGE R. BURCK.
